E. L. CALEY.

RANGE OR COOKING STOVE.

No. 17,953.

Patented Dec. 20, 1887.

UNITED STATES PATENT OFFICE.

EDWARD L. CALEY, OF PHILADELPHIA, ASSIGNOR TO BUCKWALTER & CO.,
OF ROYER'S FORD, PENNSYLVANIA.

DESIGN FOR A RANGE OR COOKING-STOVE.

SPECIFICATION forming part of Design No. 17,953, dated December 20, 1887.

Application filed October 29, 1887. Serial No. 253,792. Term of patent 7 years.

To all whom it may concern:

Be it known that I, EDWARD L. CALEY, a citizen of the United States, residing in the city and county of Philadelphia, State of Pennsylvania, have invented a new and useful Improvement in a Design for a Portable Range or Stove, which improvement is fully set forth in the following specification and accompanying photograph.

10 The leading features of my design for a portable range or stove are, first, ornamental legs; next, ornamental base; next, ornamental doors; and, next, an ornamental pipe-section, and finally an ornamental pipe-shelf.

15 A designates the legs of the stove; B, the base; C D E F, the doors; G, the top plate; H, the pipe-section, and J the pipe-shelf. The top corners of the legs have central crosses, a, surrounded by scrolls b, the front of the legs 20 having stripes a' and studs b'. From the base B depends a rim, K, the bottom of which is formed of crosses c, alternating with loops d. Above said crosses and loops is a row of festoons, e.

25 The oven-door C has a wave, f, on its upper edge, and scrolls g contiguous therewith. On the corners are dotted fields h and encircled star-shaped figures k, between which latter and the top scrolls, g, are wings m. On 30 the sides are sprays n, and on the bottom are semicircles p. On said door C is a face-plate, L, with flowers q around a central medallion, M.

The "wood" door D has a wave, r, and scroll s at top, an ornamental rim, t, at top, sides, and bottom, and a cross shaped figure, u, from the horizontal limb of which rise the columns v.

35 The ash-pit door E has upright bars w, which are ornamented by means of scrolls x x', located between said bars and alternately different.

The illuminating-door F has a panel, y, of numerous columns, at top, a panel, z, of two 40 number of columns, below the same, and a panel, z', of numerous columns, at bottom.

The pipe-section H has a central medallion, c', sprays d' above said medallion, and scrolls

e' below the same. At the sides of said section H are vertical rims f' of open scroll-work. 50

The shelf J has a vertical plate with a central row, g', of circles, top and bottom rows, h', of loops, and intermediate loops, k'.

Having thus described my invention, what I claim as new, and desire to secure by Letters 55 Patent, is—

1. In a design for a stove or range, a leg with ornamentation thereon, consisting of the crosses a, the scrolls b, the stripes a', and studs, as shown and described. 60

2. In a design for a stove or range, a body with doors, a top plate, a pipe-section, and legs, the latter having the crosses a, the scrolls b, the stripes a', and the studs b', as shown and described. 65

3. In a design for a stove or range, the base with a depending rim, the latter composed of the crosses c, the loops d, and the festoons e, as shown and described.

4. In a design for a range or stove, the oven-door C, with a wave, f, and scroll g at top, a central face-plate, with medallion and flowers, the dotted fields h, the star-shaped figures k, the wings m, and the semicircles p, as shown and described. 70

5. In a design for a range or stove, the fire-door D, with the wave r and scrolls s, the rim t, and the cross-shaped figures u v, as shown and described. 75

6. In a design for a range or stove, the ash-door E, having bars w, with scrolls x x', located between said bars and alternately different, as shown and described.

7. In a design for a range or stove, the front door, F, with a panel of numerous columns, y, at top, and panels z z', of less number of columns, below the same, as shown and described. 85

8. In a design for a range or stove, the pipe-section H, with a central medallion, c', the sprays d', the scrolls e', and rims f' of open scroll-work, as shown and described. 90

9. In a design for a range or stove, the pipe-shelf J, with a central rim, g', of circles, top and bottom rows, h', of loops, and intermediate loops, k', as shown and described. 95

10. The design for a stove or range, consisting of a body with doors having ornamentations thereon, a base with an ornamentation consisting of a rim formed of crosses, loops, 5 and festoons, legs with ornamentations of crosses, scrolls, stripes, and studs thereon, a pipe section having a medallion, with sprays and scrolls surrounding the same, and a rim ornamentation of open scroll-work, and a pipe-shelf consisting of a central rim of circles to and top and bottom loops, as shown and described.

EDW. L. CALEY.
